(57) **CLAIM**

The ornamental design for a tamper evident plastic closure, as shown and described.

DESCRIPTION

FIG. 1 is a top, front perspective view of a tamper evident plastic closure showing our new design;

FIG. 2 is a bottom, front perspective view thereof;

FIG. 3 is a front side elevational view thereof, wherein the right side, left side and rear side elevational views that are not shown are the same as the front side elevational view;

FIG. 4 is a bottom plan view thereof;

FIG. 5 is a top plan view thereof;

FIG. 6 is a top, front perspective quarter-cross-sectional view taken in the direction of line 6-6 of FIG. 1;

FIG. 7 is a top, rear perspective view of the tamper evident plastic closure in an environment of use; and,

FIG. 8 is an exploded top, side perspective view of the tamper evident plastic closure.

The broken line showing in FIG. 7 is for the purpose of illustrating environment and forms no part of the claimed design.
